VALVE MECHANISM

Harry D. Lathrop, Chicago, Ill., assignor to The Lathrop-Paulson Company, Chicago, Ill., a corporation of Illinois

Application March 25, 1940, Serial No. 325,783

4 Claims.

(Cl. 137—21)

This invention relates to valve mechanism. The valve mechanism is particularly useful in connection with a weigh can and the like.

An object of the invention is to provide a simple and effective valve mechanism which will cause the valve to remain in open position during the flowing of liquid from a container but which will automatically close the valve after the liquid has left the container. A further object is to provide valve mechanism which has a minimum of parts and which presents a minimum of projections into the interior of the container outlet during the outflow of liquid. Other specific objects and advantages will appear as the specification proceeds.

The invention is illustrated in a preferred embodiment by the accompanying drawings, in which—

Figure 1 is a broken vertical sectional view of apparatus embodying my invention; and Fig. 2, a transverse sectional view, the view being taken above the valve seat.

The present invention constitutes an improvement upon my Patent No. 2,100,142, which issued on November 23, 1937. This patent shows a container or weigh can equipped with an outlet fitting, the top of the outlet providing a seat for the valve. A valve stem guides the valve to and from its seat. A number of parts are employed for maintaining the valve in elevated position when it is raised to permit the outflow of liquid while automatically permitting the valve to move downwardly to its seat after the flow of liquid is completed. The present invention provides a structure in which the several parts of the patented structure are reduced to approximately one part and in which the main operating part is concealed or housed within a slot in the stem of the valve. In the present invention, the stem instead of being elevated with the valve is stationary and the locking mechanism is housed within a slot in the stem itself.

In the illustration given, 10 designates a container outlet, the remaining part of the container not being shown. Any type of container, whether a weigh can, as shown in my said Patent No. 2,100,142, or any other type of container, may be employed. The outlet 10 is provided at its top inner portion with a cone valve seat 11. A central hub 12 is supported in the lower central portion of the outlet 10 by three spider arms 13. The hub is centrally apertured to receive a reduced end 14 of the stem or shaft 15.

The shaft 15 is provided with a slot 16, as shown more clearly in Fig. 1.

The valve may be of any suitable type or construction. In the illustration given, a valve 17 is equipped with a tubular sleeve 18 receiving and being guided by the shaft 15. Any suitable means, not shown, for elevating the valve 17 or valve sleeve 18 may be employed.

The improved means for supporting the valve 17 in elevated position will now be described. A cup 19 provided with a perforation or perforations 20 is supported in the path of the outflowing liquid by means of a lever 21. The lever 21 is provided with a horizontal arm portion 22 equipped on its underside with a socket 23 supported upon a ball portion 24 of the shaft 15. The upper portion of the lever 21 extends substantially at right angles to the horizontal portion 22 and is provided at its top with an inclined face 25 adapted to engage the inner corner portion 26 of valve 17. The inclined face 25 is slightly indented centrally at the point indicated by the numeral 27 and substantially opposite the rounded corner portion 26 of the valve.

Operation

In the operation of the apparatus, the valve 17 is elevated by means of the tubular stem 18 to a position such as illustrated in Fig. 1. The outflowing liquid engages the cup 19 and the weight thereof tilts the vertical shaft 21 to the position illustrated in which the indented face 27 of the lever 21 engages the corner portion 26 of valve 17. The valve 17 is thus locked in elevated position during the outflow of milk or other liquid. After the liquid has passed from the container or weigh can, it discharges through the openings 20 of the cup 19 so that, within a very short time after the outflow of the milk, the cup 19 is empty. The weight of the liquid therefore serves no longer to counterbalance the shaft 21 and under the weight of the valve 17, the shaft 21 is swung inwardly within the slot 16 of shaft 15. Immediately, the valve 17 descends, being guided into position with the valve seat 11 by the engagement of shaft 15 with the tubular stem 18. When the valve is again raised, the operation will be as above described.

It will be noted that the tube 18 serves as a housing for maintaining the lever 21 within the slot of shaft 15 when the valve is in lowered position. A single lever serves as the means for support of the cup 19 and as the locking means. It is maintained out of the way of the flowing liquid, being housed within the shaft itself. The apparatus is more effective and sure in operation and much simpler in construction while at the

same time the operating parts are concealed or housed within the body of the supporting shaft.

While in the foregoing description, I have set forth certain details of structure and operation for the purpose of illustration, it will be noted that such details may be widely varied by those skilled in the art without departing from the spirit of my invention.

I claim:

1. In combination with a container outlet, a guide shaft supported therein, a valve equipped with a tube engaging said guide shaft, said guide shaft being centrally slotted, and a latch lever received within said slot and pivotally supported therein at its bottom, the top portion of said lever being provided with an inclined face adapted to engage said valve when in elevated position to lock the same in said position, a horizontal arm carried by said latch lever, and a perforated cup carried by said horizontal arm, said cup, when empty, permitting said inclined face of the latch bar to yield under the weight of said valve to permit the same to descend.

2. In combination with a container outlet, a shaft supported therein, a valve equipped with a tubular sleeve engaging said shaft and guided thereby in alignment with said outlet, said shaft being slotted and providing a fulcrum in the lower portion of the slot, a latch bar equipped with a socket at its lower point receiving said fulcrum and at its upper end with an inclined face adapted to engage said valve to support the same in raised position, said bar being provided with a horizontal arm, and a perforated cup carried by said horizontal arm adapted to swing said inclined face into locking engagement with said valve when said perforated cup

is filled but to release the same when said cup is empty.

3. In combination with a container outlet equipped with arms supporting a central collar, a shaft supported within said collar and provided with a vertical slot, a valve equipped with a sleeve receiving said shaft, a bell crank lever pivotally supported within said slot and having a horizontal arm portion extending laterally from said shaft, and a perforated cup carried by said horizontal arm portion, the lever having a vertical arm lying partly in the slot, the upper end of said arm being provided with an indentation adapted to receive the inner corner portion of said valve for supporting the same when said valve is in elevated position and liquid is flowing through the outlet into the cup, the angle of the bottom of the indentation being such as to permit the weight of the valve to force the vertical arm into the slot so that the valve will automatically fall when the flow through the outlet ceases and the cup empties.

4. In combination, a container outlet with a valve seat therein, a stem supported by said outlet and in axial alignment therewith, a valve movable to close said valve seat and having a sleeve slidable over the stem, a bell crank lever pivotally mounted on the stem and having vertical and horizontal arms, and a member carried by the horizontal arm and lying in the path of liquid passing through the outlet to hold the lever depressed so long as liquid flows through the outlet, the upper end of the vertical arm having engagement with the valve to maintain the valve in raised position so long as the lever is depressed.

HARRY D. LATHROP.
